UNITED STATES PATENT OFFICE.

LARS ANDERSON, OF CHICAGO, ILLINOIS.

MECHANICAL MOVEMENT.

1,392,389.

Specification of Letters Patent.

Patented Oct. 4, 1921.

Application filed September 1, 1920. Serial No. 407,510.

To all whom it may concern:

Be it known that I, LARS ANDERSON, a citizen of the United States, residing at Chicago, in the county of Cook and State of Illinois, have invented certain new and useful Improvements in Mechanical Movements, of which the following is a specification.

This invention relates to improvements in mechanical movements particularly adapted though not necessarily limited in its use in connection with reciprocating pumps, air compressors and vacuum producers, and one of the objects of the invention is to provide improved means whereby the rotary movement of a shaft or driven element will be caused to impart rectilinear movement to a reciprocating element or elements, such as a pump piston.

A further object is to provide improved means adapted to actuate a plurality of reciprocal plunges or pistons from a common center through the medium of an inclined crank shaft operatively connected therewith, and which mechanism will be comparatively simple, durable, cheap, and compact in construction and effective and efficient in operation, with a comparatively small degree of movement of the various parts.

A further object is to provide improved means for lubricating the various parts.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which—

Figure 1 is an irregular, vertical, longitudinal, sectional view with parts in elevation and parts broken away.

Fig. 2 is a vertical sectional view taken on line 2—2 Fig. 1.

Fig. 3 is a sectional view taken on line 3—3 Fig. 1.

Fig. 4 is a vertical sectional view taken on line 4—4 Fig. 1.

Fig. 5 is a view of a detail with parts broken away.

Fig. 6 is a view of a detail with parts broken away.

Referring more particularly to the drawings the numeral 10 designates a supporting

base upon which the structure is mounted and arranged at one end of the base is a casting 11, having a plurality of cylinders 12, therein and the casting is preferably provided with laterally projecting flanges 13, adapted to engage and rest upon supports 14, carried by the base 10, and through which flanges 13, bolts 15, are adapted to pass to engage the uprights 14, for securing the casting in position.

Air circulation passages 16, are provided in the casting and each of the cylinders is provided with the usual cooling ribs or flanges 17 arranged about their peripheries.

These cylinders may be of any desired size and one end of the cylinders is adapted to be closed by means of a head 18, secured in position by means of suitable fastening bolts 19. The head is provided with an inlet port 20 for each of the cylinders 12, controlled by a spring control valve 21, and an outlet port 22, controlled by a spring control valve 23, operating in opposition to the valve 21. The outlet passage 22, is connected by means of a port or passage 24, so that fluid which flows through the outlet passage 22, will be discharged through the passage 24, to the point of use.

Reciprocating in each of the cylinders 12, is a hollow piston 25, having a bearing 26, at one end thereof, and in each bearing an enlarged circular extremity 27, of a piston rod section 28, rests. A collar 29 is threaded into the open end of the piston and this collar 29, is provided with a seat adapted to rest against the enlarged extremity 27 of the piston rod section for holding the rod in position. If desired a lock nut or collar 30 may also be provided for holding the collar 29 against displacement.

Mounted upon the other end of the base 10, is a support 31 having an opening 32 therethrough extending longitudinally thereof and arranged at the end of this opening 32 are bearings 33, in which bearing is journaled a shaft 34, which is adapted to receive its motion from a suitable motor 35, through the medium of a sprocket chain 36, passing over a sprocket wheel 37, which is secured to the shaft 38, of the motor. The sprocket chain also passes over a sprocket wheel 39, secured to the shaft 34.

Interposed between the sprocket wheel 39, and one of the bearings 33, is a supplemental bearing which may be of any desirable or suitable construction but preferably con-

- sists of spaced members 40—41, the member 40 being secured with the sprocket wheel 39 for rotation therewith preferably by means of suitable pins 42, while the member 41 is 5 secured by means of suitable pins 43 with the support 31, so that the member 41 will be held against rotation. Balls 44 are arranged between the members 40—41 and these balls 44, are mounted in a suitable cage 45.
- 10 At the other end of the shaft 34 is a crank member 46 which is connected with the shaft for rotation therewith in any suitable manner. This crank member may be of any desired size and configuration and is provided with a bearing 47 therein arranged at an incline to the axis of rotation of the shaft 34. One end of a shaft 48 is inserted in the bearing 47, of the crank 46, and is secured to the crank for rotation therewith in any suitable manner such as by means of a key 49. The shaft is arranged in an inclined position to the axis of rotation of the shaft 34, and the extremity 50 of the shaft 48 is arranged at an angle to the length of the shaft and is 20 so disposed that the axis of the extremity 50 will be in alinement with the axis of the shaft 34. This extremity 50 is mounted in a suitable roller bearing 51, preferably supported by the cylinder casting 11, intermediate the cylinders 12. It will therefore be seen that when the shaft 34 is rotated the shaft 48 will also be rotated about the axis of the extremity 50.
- 25 Mounted upon the shaft 48, is a wabbler element 52, the interior diameter of the hub 53 of which is considerably greater than the external diameter of the shaft 48. Roller bearings 54 are connected with the element 52 and in these bearings 54, the shaft 48 is 30 journaled. Interposed between the crank 46 and the adjacent bearing 54 is another bearing embodying members 55 and 56. The member 55 is connected by means of suitable pins 57, with the crank 46 to rotate therewith, while the member 56 is connected by means of pins 58 with the hub 53 of the wabbler so as to hold the member 56 against rotation. Ball bearings 59 are interposed between the members 55 and 56 and serve to 35 take up the end thrust of the element 52.
- 40 The shaft 48 is provided with grooves 60 extending lengthwise thereof and these grooves 60, merge into a single passage 61, which discharges through the extremity 50 of the shaft 48 and in proximity to the bearing 51. The space 62 intermediate the shaft 48 and the interior of the hub 53 of the element 52, serves as an oil well adapted to be supplied with lubricant through a suitable oil cup 63. The other ends of the 45 grooves 60 terminate adjacent the bearing 54 so that when the shaft 48 is rotated the oil will be fed by gravity first to one end of the shaft through the groove 60 to lubricate the 50 bearings adjacent thereto and as the shaft

rotates and the opposite end thereof is lowered, the oil will be fed by gravity to the bearings adjacent the lowermost end.

Arranged within the element 55 are a plurality of seats 64 having a bearing 65 at 70 the bottom of each of the seats. A piston rod section 66 is provided with an enlarged circular extremity 67 resting against the bearing 65 and a collar 68 provided with a seat 69 is threaded into the end of the seat 75 44 so that the seat 69 will engage the extremity 67 of the piston rod section 66. The piston rod sections 28—66 are detachably connected together in any suitable manner and to that end the end of the piston rod section 28 is recessed as at 70 and is provided with internal screw threads, while the extremity of the piston rod 66 is reduced as at 71 and is provided with external screw threads adapted to engage the threads in the seat 70. A fastening bolt 72 may be provided for securing these two sections together.

80 With this construction it will be manifest that as the shaft 34 is rotated the crank 46 will be rotated and the shaft 48 will be 90 turned by the crank 46 about the axis formed by the end 50 of the shaft. This rotary movement of the shaft 48, will impart an oscillatory movement or a wabbling action to the wabbler element 52 and during 95 this movement of the latter element the piston rods will cause the respective pistons 25 to be reciprocated in the respective cylinders 12. As the piston in each of the cylinders 25 moves away from the head 18, the inlet 100 valve 21 will be unseated by the suction thus created and the fluid will be drawn in through the opening 73 through the port 20 and into the cylinder 12. Upon the return stroke, and when the fluid thus drawn in has 105 been compressed to the desired degree, a further movement of the piston 25 in the same direction will unseat the valve 23 to discharge the fluid through the passage 22 and into the passage 24.

110 This operation takes place in each of the cylinders 12.

By the construction of the sectional piston rods it will be manifest that the parts may be readily assembled and may be readily disconnected when desired and it will also be manifest that a very efficient and operative structure will be provided without necessitating but a small degree of movement of the pistons 25 and the operating parts 120 therefor.

115 The pistons and piston rods may be lubricated in any desirable or suitable manner preferably by means of an oil cup 74, and passages 75 in the piston rods. The circular extremities 27 and 67 of the piston rod sections may be provided with recesses 75—76 opening through their peripheries for the purpose of lightness, and these recesses may 125 serve as grease cups if desired.

The opening 32 in the support 31 through which the shaft 34 passes is of a diameter considerably greater than the external diameter of the shaft 34 so as to form an oil well adapted to be supplied with oil through the medium of an oil cup 77, and the oil is fed by means of suitable grooves 78 in the shaft 34, to the bearings at the ends of the shaft.

10 In order to relieve the piston rods and pistons together with the bearings on the ends of the piston rods against strain due to the tendency of the wabbler 52 to rotate, any suitable means may be provided such as 15 a guide 78 (see particularly Fig. 3). This guide may be constructed in any suitable manner but is preferably formed upon the supporting base 10 by providing an upwardly projecting shoulder 79 extending 20 longitudinally of the base. A removable member 80 is secured by means of fastening bolts 81 to the base to form the opposite wall of the guide. An anti-friction roller 82 is connected in any suitable manner such 25 as by means of a bolt 83 with the wabbler element 52 and this roller 82 moves back and forth in the guide 78 as motion is imparted to the wabbler.

The crank 46 is weighted as at 84 for the 30 purpose of counterbalancing the shaft and the wabbler element 52.

A shield or housing 85 is provided as a cover for the wabbler element 52 and if desired a shield or cover 86 may also be provided for the sprocket wheels 37-39 and the sprocket chain 36. If desired and as a means for holding the collar 68 against accidental displacement, a spring controlled locking dog 87 may be provided which is 40 adapted to engage teeth 88 on the collar 68.

While the preferred form of the invention has herein been shown and described, it is to be understood that various changes may be made in the details of construction and in 45 the combination and arrangement of the several parts within the scope of the claims without departing from the spirit of this invention.

What is claimed as new is:—

50 1. The combination of a rotatable shaft, a crank rotatable by the shaft, an inclined shaft connected by one end with the crank and to one side of the axis of rotation of the first recited shaft, the axis of the free 55 extremity of the inclined shaft coinciding with the axis of the first recited shaft, a bearing for the said free extremity of the inclined shaft, a wabbler element mounted upon said inclined shaft, the internal diameter of the said element being somewhat greater than the external diameter of the shaft, roller bearings interposed between the said element and the inclined shaft, a plurality of pump cylinders, pistons in the cylinders, operative connections between the said 60 cylinders, and an operative connection between the power mechanism and the

said wabbler element and the respective pistons, means exterior of the cylinders and operatively connected with the first recited shaft to rotate the latter to actuate the wabbler element.

70 2. The combination of a rotatable shaft, a crank connected with the shaft for rotation therewith, an inclined shaft connected by one end with the crank and to one side of the axis of rotation of the first recited shaft, the axis of the free extremity of the inclined shaft coinciding with the axis of the first recited shaft, a bearing for the said free extremity of the inclined shaft, a wabbler element mounted upon said inclined shaft, 75 the internal diameter of the said element being somewhat greater than the external diameter of the shaft, roller bearings interposed between said element and the last recited shaft, a plurality of pump cylinders, pistons in the cylinders, operative connections between the said wabbler element and the respective pistons, means for rotating the first recited shaft to actuate the said wabbler element, and means for restraining 80 the said wabbler element against rotation with the said inclined shaft.

85 3. The combination of a rotatable shaft, a crank connected with the shaft for rotation therewith, an inclined shaft connected by one end with the crank and to one side of the axis of rotation of the first recited shaft, the axis of the free extremity of the inclined shaft coinciding with the axis of the first recited shaft, a bearing for the said free extremity of the inclined shaft, a wabbler element mounted upon said inclined shaft, the internal diameter of the element being somewhat greater than the external diameter of the shaft, roller bearings interposed between 90 the said element and the last recited shaft, a plurality of pump cylinders, pistons in the cylinders, sectional piston rods operatively connecting the said wabbler element with the respective pistons, the sections of the 95 piston rods being detachably secured together, a motor, and an operative connection between the motor and the first recited shaft.

100 4. The combination of a rotatable shaft, a crank connected with the shaft for rotation therewith, an inclined shaft connected by one end with the crank and to one side of the axis of rotation of the first recited shaft, the axis of the free extremity of the inclined shaft coinciding with the axis of the first recited shaft, a bearing for the said free extremity of the inclined shaft, a wabbler element mounted upon and spaced from said inclined shaft, bearings between the said element and the last recited shaft, a plurality of pump cylinders, pistons in the cylinders, operative connections between the said wabbler element and the respective pistons, power mechanism, and an operative connection 110 between the power mechanism and the 115

first recited shaft to rotate the latter to actuate the said wabbler element.

5. The combination of a rotatable shaft, a crank connected with the shaft, an inclined shaft connected by one end with the crank and to one side of the axis of rotation of the first recited shaft, the axis of the free extremity of the inclined shaft coinciding with the axis of the first recited shaft, a bearing for the said free extremity of the inclined shaft, a wabbler element mounted upon and spaced from said inclined shaft, bearings between said element and the last said shaft, a plurality of pump cylinders, pistons in the cylinders, piston rods operatively connecting the wabbler element with the respective pistons, the ends of the rods having bearings in the pistons and wabbler element, power mechanism for rotating the first recited shaft 20 to actuate the wabbler element, and means for lubricating the ends of the rods through the rods.

6. The combination of a rotatable shaft, a crank connected with the shaft, an inclined shaft connected by one end with the crank and to one side of the axis of rotation of the first recited shaft, the axis of the free extremity of the inclined shaft coinciding with the axis of the first recited shaft, a bearing for the said free extremity of the inclined shaft, a wabbler element mounted upon said inclined shaft, a plurality of pump cylinders, pistons in the cylinders, and operative connections between the said wabbler element and the respective pistons, there being an oil chamber between the said inclined shaft and the wabbler element, and means whereby the said inclined shaft will supply the oil in said chamber by gravity to 40 the bearings.

7. The combination of a rotatable shaft, a crank connected therewith, an inclined shaft connected by one end with the crank to one side of the axis of rotation of the shaft, the axis of the free end of the shaft coinciding with the axis of the first recited shaft, a bearing for said free end, a wabbler element journaled upon the inclined shaft, there being a lubricant chamber in the wabbler element through which the inclined shaft passes, bearings between the wabbler and inclined shaft, cylinders, pistons in the cylinders, piston rods connecting the wabbler with the respective pistons, means for restraining 55 the wabbler against rotation, and means whereby the rotation of the said inclined shaft will cause the lubricant in the said chamber to be fed by gravity first to one end and then to the other end of the inclined 60 shaft.

8. The combination of a rotatable shaft, a crank connected therewith, an inclined shaft connected by one end with the crank to one side of the axis of rotation of the shaft, the

axis of the free end of the shaft coinciding 65 with the axis of the first recited shaft, a bearing for said free end, a wabbler element journaled upon the inclined shaft, there being a lubricant chamber in the wabbler element through which the inclined shaft 70 passes, bearings between the wabbler and inclined shaft, cylinders, pistons in the cylinders, piston rods connecting the wabbler with the respective pistons, means for restraining the wabbler against rotation, and means whereby the rotation of the said inclined shaft will cause the lubricant in the said chamber to be fed by gravity first to one end and then to the other end of the inclined 75 shaft, the last recited means embodying 80 passages in the said inclined shaft having communication with the said chamber.

9. The combination of a rotatable shaft, a crank connected with the shaft, an inclined shaft connected by one end with the crank 85 and to one side of the axis of rotation of the first recited shaft, the axis of the free extremity of the inclined shaft coinciding with the axis of the first recited shaft, a bearing for the said free extremity of the 90 inclined shaft, a wabbler element mounted upon said inclined shaft and spaced therefrom, a plurality of pump cylinders, pistons in the cylinders, separable sectional piston rod connections between the wabbler element 95 and the respective pistons, power mechanism connected with the first recited shaft and remote from the wabbler element for rotating the first said shaft, and a freely movable protecting hood extending over and 100 housing the said wabbler element.

10. The combination of a rotatable shaft, a crank connected with the shaft, an inclined shaft connected by one end with the crank and to one side of the axis of rotation of the first recited shaft, the axis of the free extremity of the inclined shaft coinciding with the axis of the first recited shaft, a bearing for the said free extremity of the inclined 105 shaft, a wabbler element mounted upon said inclined shaft and spaced therefrom, a plurality of pump cylinders, pistons in the cylinders, operative connections between the wabbler element and the respective pistons, power mechanism connected with the first 110 recited shaft remote from the wabbler element for actuating the former, and means for restraining the said wabbler element against rotation, the said means embodying 115 an anti-friction roller connected with the wabbler and a guide in which the roller moves, said guide having a removable section.

In testimony whereof I have signed my name to this specification, on this 27th day 125 of August, A. D. 1920.

LARS ANDERSON.
